UNITED STATES PATENT OFFICE.

JAMES WILLIAM TATUM, OF DURHAM, NORTH CAROLINA.

COAL-GRAVE.

1,261,068.

Specification of Letters Patent.

Patented Apr. 2, 1918.

Application filed May 24, 1917. Serial No. 170,686.

To all whom it may concern:

Be it known that I, JAMES W. TATUM, a citizen of the United States, residing at Durham, in the county of Durham and State of North Carolina, have invented certain new and useful Improvements in Coal-Grates; and I do declare the following to be a full, clear, and exact description of the invention, such as will enable others skilled in the art to which it appertains to make and use the same.

My invention relates to grates and more particularly to that class of grates which are of the basket form, and which are designed to be used in open fire places and the like.

It has been found that the parts of the grate most readily affected by the heat of the fire are the bottom parts and there has been a great source of trouble and inconvenience inasmuch as the bottom of the grates in use at the present time is burned out which impairs the efficiency of the grate, as an entirely new grate will have to be substituted; and it is the primary object, therefore, of my invention to provide a grate in which these difficulties are overcome by employing a removable bottom for the grate.

A further object of my invention is to provide a grate of this character in which a removable bottom portion is slidable on the grate frame and which may be rocked or tilted vertically so as to provide for an effective shaking of the grate.

A still further object of the invention is to provide in a grate of this character a slidable removable bottom which may be rocked so as to dump the grate without entirely removing the bottom therefrom.

With these and other general objects in view which will appear from the description my invention resides in the novel combination, construction and arrangement of parts to be more fully hereinafter described and claimed when taken in connection with the accompanying drawings which form a part of this application.

Figure 1 is a front elevation showing my improved grate as applied in a fireplace;

Fig. 2 is a vertical sectional view taken on the line 2—2 of Fig. 1;

Fig. 3 is a horizontal sectional view on the line 3—3 of Fig. 1;

Fig. 4 is a vertical sectional view on the line 4—4 of Fig. 1; and,

Fig. 5 is a transverse sectional view on the line 5—5 of Fig. 4.

In detail my improved grate comprises a horizontal base frame or section 1 composed of a pair of side bars 2 supported on legs 3 which may be attached to the ends of the bar or may be formed integrally therewith as may be found desirable. Intermediately of the ends of the bars 2 which are spaced considerably from one another and extended parallel, is secured a transverse connecting bar 4 having its ends extended beyond the side bars and provided with hook lugs 5 for a purpose to be hereinafter described. At one end the bars 2 are provided with upright vertically extending continuations 6 connected transversely at their top by bars 7 and extending downwardly in vertical parallel spaced relation from the lower bar 7 and joined thereto in any suitable manner are a series of bars 8 having their lower terminals 9 spaced above the plane of the side bars 2 and extended inwardly to form fingers which assist in supporting the coals at the front of the grate. The spaced bars 8 coact with the upright members 6 and the transverse bars 7 to form an effective guard or front for the grate and it will be obvious that this structure, owing to the transverse bar 4 provides a rigid frame for the grate which is adapted to be inserted into a fireplace or the like, with the vertically extending front guard toward the front of the fireplace.

In some instances when it may not be desirable to use the legs 3 for supporting the grate, I may so construct the grate as to dispense with these legs and support the grate by means of the lugs 5 and lugs 10 which are formed on the upright members 6, it being understood that suitable attaching means will be provided in the fireplace for supporting the grate by means of these lugs. The forward ends of the side bars 2 are extended slightly beyond the upright continuations 6 so as to form projecting lugs 11 for a purpose to be hereinafter described.

The removable grate bottom comprises a rectangular frame 12 having spaced front and rear transverse bars 13 connected by longitudinal grate bars 14. The ends of the bars 13 extend slightly beyond the adjacent bars 14 to provide bearing lugs which are adapted for sliding on the side bars 2, with the extended ends of the rear bar 13 rest-

ing upon the surface of the side bars 2 and adapted to slide and rock thereon and with the front bar 13 having its ends supported on the forwardly extending lugs 11 of said 5 side bars.

Owing to the spaced relation of the lower terminals of the front bars 8 above the plane of the side bars 2 it will be apparent that the grate bottom may be slid forwardly 10 and rearwardly upon the grate frame below the lower terminals of the front bars 8 without coming into contact therewith. The front bar 13 of the grate bottom is provided with a suitable handle member 15 which 15 may be suitably engaged for the manipulation of the grate bottom by hand or with the poker or other suitable tool as desired. The bars 14 of the grate bottom are so disposed relative to the front bars 8 as to receive the bars 8 therebetween so that when 20 it is desired to shake the grate it is merely necessary to engage the handle member 15 and lift the bottom in a vertical plane with the rear bar of the bottom resting at its 25 ends on the side bars 2 whereby the bottom may be rocked in a vertical plane to effectually shake and dislodge any clinkers thereon.

When it is desired to dump the grate it is 30 merely necessary to engage the handle and slide the bottom forwardly whereupon the front bar will become disengaged from the lugs 11 and when the bottom has been slid forwardly to the desired point the front 35 thereof may be lowered with the ends of the rear bar pivotally on the side bars 2 whereupon the ashes and other matter on the grate will be effectually dumped. When merely shaking the grate, the latter is disengaged 40 from the lugs 11 and either moved forwardly and rearwardly or rocked upon the bar 4 and the projecting ends of the rear bar 13.

It may be found expedient to slide the 45 bottom forwardly and then tilt the same in a vertical plane upwardly so as to dump to the rear of the grate. Either of the two methods may be employed to suit the individual conditions.

50 By the foregoing construction as described it will be seen that I have provided a grate which is easy and cheap to manufacture, simple to manipulate and most efficient in operation and one in which the

bottom may be replaced if desired from time 55 to time without in any way changing the structural details of the base of the grate, and while I have described and shown certain specific details of form entering into the construction of the device, I do not desire 60 to limit myself to these, but I intend that any such changes may be made in the details thereof as will be included within the scope of the invention as claimed.

What I claim is:

1. In a fire place grate, a pair of parallel 65 grate supporting bars adapted to extend from front to rear of the fire place, means for supporting said bars a distance above the fire place bottom, a third grate supporting bar at right angles to the others and joined at its ends thereto near their centers, a grate bottom resting slidably on said third bar between said pair of bars and having front and rear projecting lugs resting slidably on said pair of bars; together with a front guard for retaining the coals on the 70 grate, said guard being constructed to permit vertical movement of said grate bottom.

2. In a fire place grate, a pair of parallel 75 horizontal grate supporting bars adapted to extend from front to rear of the fire place and means for supporting said bars a distance from said fire place bottom, a pair of 80 vertical end bars rising from said grate supporting bars near the front ends of the latter, a horizontal bar extending between the upper ends of said end bars, and vertical bars depending from said last named horizontal bar and forming therewith a coal retaining guard, the lower ends of said vertical bars being spaced above the plane of said 85 grate supporting bars and being free of connection; together with a grate bottom having rear projecting lugs slideable and rockable on said grate supporting bars and having front projecting lugs resting removably on the front ends of said supporting bars in front of said vertical end bars, said grate 90 bottom being slideable between said end bars. 95

In testimony whereof I have hereunto set my hand in the presence of two subscribing witnesses.

JAMES WILLIAM TATUM.
